UNITED STATES PATENT OFFICE

JOHN J. HYNES, OF UNIVERSITY CITY, MISSOURI

NECKTIE

Application filed August 26, 1927. Serial No. 215,584.

This invention relates to neckties and especially to the type commonly designated four-in-hand ties. The operation of forming a tight knot with such a tie puts the material thereof under great stress and has a tendency to tear, wrinkle or permanently distort the fabric thereof and to break the stitching that holds the parts together. The principal objects of the present invention are to protect the body and lining of the tie from undue stress; and provide for the knotted material to resume the shape it had before knotting; and to prolong the effective life of the tie. It consists principally in providing the tie with a member that is relatively inelastic and is normally slack but adapted to become taut and take up the tensile stress before the fabrics of the tie are stretched to their elastic limits. It also consists in joining the somewhat elastic facing and lining of the tie by means of a relatively inelastic tape that passes through the same in a series of normally slack loops that lie in substantially the plane of the longitudinal axis of the tie. It also consists in the combination and arrangements of parts hereinafter described and claimed.

In the accompanying drawing wherein like reference numerals refer to like parts wherever they occur,

Fig. 1 is a view of the back of a tie embodying my invention;

Fig. 2 is an enlarged view of an end portion with the folds broken away; and

Fig. 3 is an enlarged longitudinal sectional view of an end portion.

My tie comprises a facing or body 1 of silk or other suitable material and a lining 2 over the back of which the sides of the facing material are folded. These folds 3 are wide enough to overlap each other. As usual, the facing material is arranged on the bias, whereby it has a certain amount of resiliency that enables it to stretch to a limited extent lengthwise of the tie and still resume its original condition when the tension thereon is relieved.

The lining is also made of material that permits of a certain amount of stretching lengthwise of the tie and has the resiliency

required to restore it to initial condition. The woolen fabric commonly known as interlining and commonly used in making ties is suitable for this purpose, especially when arranged on the bias.

According to the present invention, a relatively inelastic tape or lace 4 is looped back and forth through the overlapped portions of the back folds of the facing material and the lining material in such manner that the tape extends lengthwise of the tie near the longitudinal center line thereof and each alternate loop thereof is visible on the back of the tie. Preferably the individual loops are an inch or more in length, with only such amount of slack as may be required to permit such stretching of the body and lining materials as may be desirable for forming a knot without undue straining thereof.

By the arrangement described, the tape serves the purpose of the usual stitching, in so far as concerns the function of holding the body and lining materials together; but it operates very differently from the ordinary stitching. When the tie material is subjected to longitudinal pull, the initial tension stress thereon is mainly taken up by the resiliency of the tie material, that is, by the materials of the facing and of the lining, without any considerable portion of such stress being taken by the normally slack tape. As the stretching of the tie material progresses and before the tension on such materials reaches the elastic limits thereof, the slack is taken out of the individual loops of the tape and the tape becomes taut, whereupon the facing and lining materials are relieved from further tension thereon and such further tension is taken by the tape.

It is noted that at the beginning of this operation, the materials are not clamped firmly together, due to the slack in the loops, but that as the stretching of the tie material progresses, the slack is gradually taken up and the materials are clamped more and more firmly together and thus brought into a substantial frictional engagement that causes the stress to be distributed between them. It is also noted that during the earlier part of this action, the facing and lining fabrics

have considerable freedom in sliding and adjusting themselves to such positions as will equalize the stresses thereon; and it is particularly noted that, due to this freedom of movement on the tape and to their frictional engagement with each other, stresses originating in the facing material or in the lining material are readily transmitted to other material and to the tape, so that all of these parts can be counted on to take their proper share of the stresses. When the tension is released the resiliency of the materials tends to restore the tie to its proper shape.

The element herein designated "tape" may consist of any of numerous materials provided it is pliable, relatively inelastic and of sufficient tensile strength to withstand the pull occasioned by the tying and adjusting of the tie. I prefer the material known as "lingerie ribbon" as it is sufficiently inelastic and strong, requires only a small hole to pass through, permits the tie materials to slip readily thereon, attracts attention to the manner of making the tie and especially to its mode of operation, and may be made as an ornamental feature thereof. One or more strong threads, string, lace and ribbon may be used for the "tape" of my tie.

At one end of the tie, preferably the narrow end, the tape is formed into a loop 5 suitable for hooking over a big hook or the like. When the tie is suspended by such loop, the tie materials may slip readily on the tape and readjust themselves to their initial position under the influence of their resiliency.

What I claim is:

1. A necktie comprising a resilient body portion and a resilient lining therein loosely laced together by a relatively inelastic lace adapted to permit limited stretching of the body portion and lining and prevent excessive stretching thereof.
2. A necktie comprising a resilient body portion, a resilient lining, and a substantially inelastic tape disposed lengthwise of the tie and laced through said body portion and said lining in a series of normally slack loops that lie in a plane transverse to the plane of said body portion.
3. A necktie comprising a resilient lining, a resilient body portion folded over said lining, and a substantially inelastic tape disposed lengthwise of the tie and extending through said lining and the folds of said body portion in a series of normally slack loops that lie in a plane transverse to the plane of said body portion, said tape being arranged to become taut before said lining and body are stretched to their elastic limits.
4. A necktie comprising a stretchable lining, a stretchable facing enclosing said lining, and a relatively inelastic tape laced through said lining and the folds of said facing in a series of widely spaced loops that are normally slack but become taut when the

lining and facing are stretched a predetermined extent.

5. A necktie comprising a resilient body portion and a resilient lining therein loosely laced together by a relatively inelastic lace adapted to permit limited stretching of the body portion and lining and prevent excessive stretching thereof, said tape having a loop at its end.

6. A necktie comprising a resilient body portion folded on itself and loosely laced together by a relatively inelastic lace adapted to permit limited stretching of the body portion and prevent excessive stretching thereof.

7. A necktie comprising a resilient body portion folded on itself and a substantially inelastic tape disposed lengthwise of the tie and laced through said body portion in a series of normally slack loops that lie in a plane transverse to the plane of said body portion.

8. A necktie comprising a resilient body portion folded on itself and a substantially inelastic tape disposed lengthwise of the tie and extending through the folds of said body portion in a series of normally slack loops that lie in a plane transverse to the plane of said body portion, said tape being arranged to become taut before said body is stretched to its elastic limit.

Signed at St. Louis, Missouri, this 24th day of August, 1927.

JOHN J. HYNES.
